US0D1051244S

(12) **United States Design Patent** (10) **Patent No.:** **US D1,051,244 S**
(45) **Date of Patent:** **** Nov. 12, 2024**

(54) **SET OF MODEL VEHICLE AXLE CARRIERS**

(71) Applicant: **TRAXXAS, L.P.**, McKinney, TX (US)

(72) Inventors: **Adam Cole Ewing**, McKinney, TX (US); **Kent Poteet**, Lucas, TX (US); **Casey Christen Jens Christensen**, McKinney, TX (US); **Otto Karl Allmendinger**, Rowlett, TX (US); **Skylar Hagler**, Anna, TX (US); **Jory Sprowl**, Honey Grove, TX (US); **Noah House**, Sachse, TX (US)

(73) Assignee: **TRAXXAS, L.P.**, McKinney, TX (US)

(**) Term: **15 Years**

(21) Appl. No.: **29/847,773**

(22) Filed: **Jul. 27, 2022**

(51) **LOC (14) Cl.** **21-01**

(52) **U.S. Cl.**

USPC **D21/562; D21/561**

(58) **Field of Classification Search**

USPC D21/433, 495, 533, 561, 562, 563; D12/92, 114, 159, 160, 172, 190, 204

CPC A63H 17/262; A63H 17/26; A63H 17/002; A63H 29/24

Assistant Examiner — Gregory G McLemore

(74) *Attorney, Agent, or Firm* — Daryl R. Wright; Greg Carr

(57) **CLAIM**

The ornamental design for a set of model vehicle axle carriers as shown and described.

DESCRIPTION

FIG. 1 is an upper, right, front perspective view of a set of model vehicle axle carriers showing our new design;

FIG. 2 is a right-side elevation view thereof;

FIG. 3 is a left-side elevation view thereof;

FIG. 4 is a lower plan view thereof;

FIG. 5 is an upper plan view thereof;

FIG. 6 is a rear elevation view thereof;

FIG. 7 is a front elevation view thereof;

FIG. 8 is an upper, left, rear perspective view thereof;

FIG. 9 is a lower, left, rear perspective view thereof; and,

FIG. 10 is a lower, left, front perspective view of a set of model vehicle axle carriers.

In the drawings, the broken lines illustrate portions of the set of model vehicle axle carriers that form no part of the claimed design.
